SPRING MOTOR ASSEMBLAGE FOR
CLOCKWORK MECHANISMSMerritt Van Valkenburgh, Upper Nyack, N. Y.,
assignor to M. H. Rhodes Incorporated, Hartford, Conn., a corporation of Delaware

Application October 18, 1951, Serial No. 251,907

5 Claims. (Cl. 185—45)

1

This invention relates to manually wound clockwork and timer mechanisms and more specifically to improvements in the power means and drive assemblages for these and other spring driven mechanisms.

It is the aim of the invention to provide a simple, compact and economical power assemblage for a clockwork mechanism which will not only improve the operating characteristics of the mechanism but will reduce the overall manufacturing costs of the mechanism.

Another object of the invention is to provide a clockwork mechanism with a spring motor drive which requires no more space than conventional spring motors yet which may be wound to store a greater amount of energy than will conventional spring motors utilized in installations having the same space limitations.

Another object of the invention is to provide a clockwork mechanism with a spring motor drive assemblage which diminishes the possibility of breakage due to jarring, etc., which will withstand a great amount of wear and hard usage without losing any of its operating characteristics and which will operate efficiently under atmospheric conditions wherein the electrostatic and magnetic conditions adversely affect conventional constructions and under temperature conditions which cause breakage in conventional spring motor constructions.

It is a further object of the present invention to provide a spring motor construction for clockwork mechanisms having the foregoing characteristics and which may be constructed of inexpensive materials and which may be easily and economically fabricated and assembled as a unit and in the clockwork mechanism.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a front elevational view of a clockwork assemblage which incorporates a spring motor constructed in accordance with the present invention;

Fig. 2 is an enlarged vertical cross-sectional view taken along the line 2—2 of Fig. 1;

Fig. 3 is a transverse sectional view taken along the line 3—3 of Fig. 2;

Fig. 4 is a transverse sectional view taken along the line 4—4 of Fig. 2; and

2

Fig. 5 is a perspective view of the main spring utilized in the construction of the clockworks.

For purposes of exemplification, the present invention is shown as incorporated in the construction of a timer 10. By "timer" is meant a device utilizing a clockwork mechanism to measure a preselected time interval. Since the present invention concerns only the clockwork mechanism of the timer, the elements utilized for indicating the time and for signalling the end of a measured interval are not shown or discussed herein. However, it should be understood that in respect to these elements the timer mechanism shown in the drawings utilizes conventional parts well known in the art.

The clockworks incorporated in the present construction are mounted on spaced apart front and rear frame plates 11 and 12. The clockworks includes an arbor 13 which is journaled in the front and rear frame plates and which is operatively connected to a main spring or power spring 14 as will appear in detail hereinafter. In the particular embodiment shown, the arbor 13 is provided with diametrically opposed flats 15 adjacent its front end to receive a conventional timer setting knob or pointer which can be manually rotated to a set position whereby the spring 14 is energized. Upon release of the setting knob and arbor, the spring operates to mechanically return the setting knob and arbor to the original "at rest" or starting position. The arbor 13 by means of a friction clutch 15 is drivingly connected to a gear 16 which is included in a conventional time train indicated generally by the reference numeral 17. If desired, the clutch 15 may be of the "one-way" variety, involving the use of a ratchet. The time train comprises a plurality of intermeshed gear wheels and pinions which are supported on staffs journaled in the frame plates 11 and 12. The time train drives an escape wheel 18, and a retarding device or clutter 19 is disposed adjacent the escape wheel 18 for oscillatory movement so as to engage the escape wheel and thereby retard or impede the operation of the gear train to prevent too rapid dissipation of the energy stored by the main spring 14 whereby the arbor and setting knob are returned to initial position in a time controlled manner.

In accordance with conventional practice the rear end of the arbor 13 may extend through the rear frame plate 12 so as to receive timing disks or other well known elements utilized in signal apparatus or circuit making or breaking apparatus which is to be excited at the completion of a measured time interval.

In accordance with the present invention, the main spring or power spring 14 comprises a wire of circular cross section such as piano wire which is formed into multi-coil volute configuration having a large end coil 20 and a small end coil 21. The large end coil terminates in a radially inwardly extending ear 22 and the small end coil terminates in a radially outwardly extending ear 23 which are arranged to secure the spring within an encasement comprising a generally cup-shaped housing 24 and a cover 25.

As is best shown in Figs. 1, 2 and 4, the spring housing 24 has a circular end wall 26 provided with a central opening 27 to receive the front end portion of the arbor 13 so that the end wall 26 may be disposed adjacent the rear surface of the front frame plate 11. The wall 26 has a rearwardly extending generally cylindrical skirt 28 to complete the cup-shaped configuration of the housing, and the front plate 11 has a plurality of rearwardly extending ears 29 which engage the skirt 28 to locate and position the housing 24. The end wall of the housing has a forwardly extending ear 30 which engages in any one of the frame openings 31 from which an ear 29 is struck so as to prevent rotation of the spring housing relative to the frame. The torque on the spring 14 can be adjusted by selecting the opening 31 which receives the ear 30.

The housing wall 26 is also provided with a pair of rearwardly extending ears 32 and 33 which are circumferentially spaced from each other and which are radially inwardly spaced from the skirt 28. The ears 32 and 33 provide means for securing the large end of the volute spring 14 within the housing, the spring ear or appendage 22 engaging the ear 32 with the largest coil 20 disposed between the skirt 28 and the ears 32 and 33, as shown in Fig. 4.

The cover member 25 is generally circular and of dish-like configuration and is provided with a central opening 36 which describes the central zonal portion of a circle or disk. The opening 36 is provided with such configuration so that the cover can be slidably fitted over arbor portion 35 to abut against the enlarged central portion 37 of the arbor. It will be noted that arbor portion 35 is of reduced diameter and has diametrically opposed flats 38 insertable within the opening. Arbor shoulder 39 is thus provided to engage the rear surface of the cover 25 so that in the assembled relation shown in Fig. 2 the cover will turn with the arbor and will be held within the confines of the housing skirt 28 so as to retain the spring in axially compressed condition within the housing. The cover is also provided with a generally L-shaped opening 40 (Fig. 3) and a forwardly extending ear 41 so as to receive and engage the ear or appendage 23 formed on the small end of the volute spring 14. The smallest coil 21 is thus positioned about the enlarged section of the arbor and rotation of the arbor will effect rotation of the main spring with the main spring secured to the cover which, in turn, is secured to the arbor for rotation therewith. Accordingly then, if the arbor is rotated clockwise as shown in Fig. 2, the main spring will be wound within the spring housing so as to store energy to return the setting knob to the starting position as influenced by the time train and the retarding mechanism.

It will be noted with reference to Fig. 2 that in the axially compressed condition of the spring within the housing the coils adjacent the large end of the spring are disposed in a semi-stacked

relation so as to define a hill 45 and it will also be noted that the coils adjacent the hill 45 are thrust forwardly so as to define a valley 46. A second hill 47 is formed radially inwardly of the valley 46 and an innermost valley 48 is formed in the compressed spring and the coils adjacent the small end of the spring are in stacked relation extending toward the cover 25. It has been discovered that the volute piano wire spring utilized in the present construction may be more compactly compressed than can any main springs known, and it is believed that the characteristic compressibility of the spring arises due to the aforescribed formation of the hills and valleys in the compressed condition. Such hill and valley configuration will arise only in the use of a volute spring having circular cross section whereby the adjacent coils of the spring are permitted to slide past or overlap one another to thus form the above mentioned hills and valleys. As a result of the increased compressibility obtained in the aforescribed assemblage, a larger spring can be used in the space available for assembling conventional main springs and consequently a greater amount of energy may be stored.

The sliding relation of the coils of the spring provides greater efficiency as compared to conventional springs in that the sliding friction between adjacent coils is materially reduced. The friction is reduced to such an extent that in most installations it is unnecessary to lubricate the coils whereas the conventional flat spiral main spring must be well lubricated between the coils in order to obtain uniformity of torque delivery in operation.

It has also been found that the spring utilized in the present power assemblage is less susceptible to breakage due to atmospheric and temperature conditions than are conventional springs. This advantage arises because of the circular cross-sectional configuration of the spring whereby the greatest strength results from the material available for fabricating the spring. The increased strength also diminishes the likelihood of breakage due to jarring over winding and due to electrostatic and magnetic changes accompanying changes in atmospheric conditions. In addition, the circular piano wire spring is relatively inexpensive as compared with the flat spiral springs conventionally used in clockwork mechanisms and it has been found that the spring motor assemblage including the housing and cover can be fabricated and assembled with greater economy whereby the cost of manufacturing clockwork mechanism is materially reduced.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

70 I claim as my invention:

1. Power means for a time movement comprising a volute wire coil spring having a generally circular cross section with adjacent turns partially overlapping each other, a pair of closure members disposed on opposite ends of said

spring arranged to axially compress said spring into a generally circular body having radially spaced annular hills and annular valleys, means on one of said closure members for securing one end of the spring against movement, and means secured to the other end of said spring for winding the same whereby energy is stored within the spring.

2. In a spring driven mechanism of the type having a frame and a manually settable arbor journaled in the frame and arranged to be mechanically returned from a set position to an initial position under control of the mechanism, improved power means comprising an axially compressed volute coil spring fabricated from wire having a generally circular cross section with adjacent turns partially overlapping and touching each other to form radially spaced annular hills and annular valleys, said spring being disposed around the arbor with the one end thereof secured to the frame and the other end of said spring being connected to the arbor whereby manual rotation of the arbor in one direction will wind the spring and condition the same to drive the mechanism and thereby rotate the arbor in the opposite direction.

3. In a spring driven mechanism of the type having a frame and a manually settable arbor journaled in the frame and arranged to be mechanically returned from a set position to an initial position under control of the mechanism, an improved power assemblage comprising a generally cup-shaped spring housing encircling the spring and having its bottom wall secured to the frame, an axially compressed volute coil spring fabricated from wire having a generally circular cross section, said spring encircling the arbor and being disposed within said housing with the one end secured thereto, and the other end of said spring being connected to the arbor whereby manual rotation of the arbor in one direction will wind the spring and condition the same to drive the mechanism and thereby rotate the arbor in the opposite direction.

4. In a clockwork mechanism of the type having a frame and a manually settable arbor journaled in the frame and arranged to be mechanically returned from a set position to an initial position under control of the mechanism, an improved power assemblage comprising a generally cup-shaped spring housing secured to the

frame and encircling the arbor, an axially compressed volute coil spring fabricated from wire having a generally cylinder cross section, said spring being disposed within said housing and encircling the arbor, means securing the end of said spring adjacent the largest coil to the bottom wall of the housing, a cover member for said housing secured to the arbor for rotation therewith, and the small end coil of said spring being attached to said cover whereby manual rotation of the arbor in one direction will wind the spring and condition the same to drive the mechanism and thereby rotate the arbor in the opposite direction.

15 5. In a clockwork mechanism of the type having a pair of spaced frame plates and a manually settable arbor journaled in the frame plates and arranged to be mechanically returned from a set position to an initial position under control of the mechanism, an improved power assemblage comprising a generally cup-shaped spring housing, means on one of said frame plates for receiving said housing with its bottom wall adjacent said frame plate and with its peripheral wall encircling the arbor, means on said housing engaging said one frame plate to prevent movement of the housing relative thereto, an axially compressed volute piano wire coil spring disposed within said housing and encircling the arbor, means on the large end of said coil spring engaging the bottom wall of the housing and securing the spring against movement relative thereto, a generally circular cover for said housing concentrically secured to said arbor, and means interconnecting the smallest coil of said spring and said cover whereby manual rotation of the arbor in one direction will wind the spring and condition the same to drive the mechanism and thereby rotate the arbor in the opposite direction.
